This application is also related to the following Divisional Design Applications: Pro Power Center (Rectangular Display), application Ser. No. 29/163,011; Pro Power Center (Oval Display Rack Mount), application Ser. No. 29163,010; Tall Pro Power Center (Oval Display Table Mount), Ser. No. 29/163,002; Pro Power Center (No Display), and application Ser. No. 29/162,997.

FIG. 1 is a perspective view of a pro power center (oval display table mount), in accordance with the present invention.

FIG. 2 is a plan view of a pro power center (oval display table mount), in accordance with the present invention.

FIG. 3 is an underside view of a pro power center (oval display table mount), in accordance with the present invention.

FIG. 4 is a side view of a pro power center (oval display table mount), in accordance with the present invention.

FIG. 5 is a corresponding side view a pro power center (oval display table mount), in accordance with the present invention.

FIG. 6 is a rear view of a pro power center (oval display table mount), in accordance with the present invention; and, FIG. 7 is a frontal view of a pro power center (oval display table mount), in accordance with the present invention.
